UNITED STATES PATENT OFFICE.

HARRY A. WATSON, OF PITTSBURG, PENNSYLVANIA.

INDICATOR.

No. 829,243.

Specification of Letters Patent.

Patented Aug. 21, 1906.

Application filed November 10, 1904. Serial No. 232,248.

To all whom it may concern:

Be it known that I, HARRY A. WATSON, a citizen of the United States of America, residing at Pittsburg, in the county of Allegheny and State of Pennsylvania, have invented certain new and useful Improvements in Indicators, of which the following is a specification, reference being had therein to the accompanying drawings.

10 This invention relates to certain new and useful improvements in indicators, and more particularly to that type which is adapted for use in street-cars, railway-cars, and like places where it is desired to display the 15 names of streets or stations at which the cars will stop.

The object of my invention is to provide an indicator of this type which is adapted to be actuated by the motorman of a street-car 20 or when used upon railway-trains by a brakeman, and the indicator is adapted to display at each actuation the name of the street or station at which the car will next stop, and in constructing my improved indicator I have 25 employed novel means for operating the same and for reversing the mechanism when the cars are about to make a return trip.

The invention finally consists in the novel construction, combination, and arrangement 30 of parts, which will be hereinafter more fully described and then specifically pointed out in the claims, and, referring to the drawings accompanying this application, like numerals of reference designate corresponding parts 35 throughout the several views, in which—

Figure 1 is a perspective view of my improved indicator, illustrating the same secured in a street-car. Fig. 2 is a vertical sectional view of the end of a street-car, showing 40 my improved indicator in position and the mechanism used for actuating the same. Fig. 3 is a vertical sectional view of my improved indicator. Fig. 4 is a horizontal sectional view of the same. Fig. 5 is a diagrammatical 45 view of the wiring employed to operate my improved indicator. Fig. 6 is an end view of the indicator looking at the left-hand end of the mechanism shown in Fig. 3.

To put my invention into practice, I preferably employ a rectangular casing consisting of a front and rear wall 1 and 2, respectively, end walls 3 and 4, and the top and bottom plates 5 and 6. The top 5 of the casing is provided with lugs 7 7, whereby the casing 55 can be secured to the end of a car, and in describing the invention we will assume that

the indicator is to be employed in a street-car. The indicator can be placed in either end of the car and is generally secured above one of the doors of the car. The front wall 60 of the indicator is preferably formed of a glass plate which is painted black or otherwise darkened with the exception of the oblong space designated by the reference-numeral 8. This space is clear, whereby the 65 names of streets may be displayed through said casing. Above the space designated by the reference-numeral 8 the words "Next stop" are arranged, or suitable words indicating the next stop will be, for instance, 70 "Wood street." In the casing of my improved indicator and between the end walls 3 and 4 are rotatably mounted the shafts 9 and 10, which carry an apron 11, one end of the apron being secured to the shaft 9, while 75 the opposite end is secured to the shaft 10, and upon this apron are arranged the names of the streets or stations of the route over which the car passes. These shafts are arranged one above the other, whereby the 80 apron will travel vertically before the space 8 of the front of the casing. Upon the ends of the shafts 9 and 10 are arranged the ratchet-wheels 12 12, the teeth of which are identical, and upon the opposite end of the shafts are 85 arranged the ratchet-wheels 14 14, the teeth of these wheels being reverse to those of the wheels 12 12. To the end walls 3 and 4 of the casing are secured the guides 15, and in these guides are mounted the posts 16 and 17. 90 The post 17 is provided with the spring-pressed pawls 18, which are normally held in engagement with the teeth of the ratchet-wheels 12 12. The post 16 is provided with spring-pressed pawls 19, which are reversely 95 arranged to the pawls 18, the pawls 19 being pulling-pawls—that is, they operate to turn the ratchets by the downward movement of the post 16. In each end of the casing are arranged the solenoids 20 and 21, the solenoid 21 being connected by an L-shaped arm 22 to the post 17, while the solenoid 20 is connected by a similar arm to the post 16. These solenoids are of the ordinary construction, and the L-shaped arms 22 are adapted to 100 carry suitable cores, which may be attracted by the energizing of the solenoids. In the diagrammatic view, Fig. 5, these cores are designated by the reference-numerals 23 and 24. The core 23 is retained in an elevated 110 position by a spiral spring 25 and the core 24 retained in a lowered position by the spiral

spring 26, mounted upon their respective arms. Between the posts 16 and 17 and the ratchet-wheels 12 and 14 are the plates 27 and 28, said plates having slots 29 formed therein. The plates are supported and connected together by the arm 30, which is carried by a shaft 31, that is pivotally mounted upon the bottom 6 of the casing, said shaft extending without the casing to the front of the casing and carrying a suitable button 32. The opposite end of the shaft 31 is provided with the insulated arms 33, which carry upon their outer ends the contact-blocks 34 and 35. Each of the contact-blocks 34 35 is made in two sections, and the sections of each block are insulated from one another. One section of the block 35 is connected by a wire 47 to a block 46', and one section of the block 34 is connected to the same block 46', while the other section of the block 35 is connected by a wire 48 to a block 46, and the other section of the block 34 is connected by a wire 47' to said block 46. Upon the bottom 6 of the casing are mounted the contact-blocks 36 and 37, which are connected by wires 38 and 39, respectively, to the solenoids 20 and 21. The blocks 36 and 37 are also each in two sections, the sections of each block being insulated from one another, the terminals of the wire 38 being connected, respectively, to the two sections of the block 36 and the terminals of the wire being connected, respectively, to the two sections of the block 37.

Reference will now be had to Fig. 2 of the drawings, wherein I have illustrated the mechanism employed for actuating my improved indicator, and while I have only illustrated this mechanism as being applied to one end of a car I wish it to be understood that the same may be employed upon the opposite end, whereby should the car be operated from the opposite end my improved indicator can be readily actuated. Beneath the platform of the car is pivotally mounted, as indicated at 40, an insulated lever 41, carrying a contact-block 42, composed of two metallic sections insulated from one another and mounted adjacent to the opposite end of the lever and within the platform 43 is a sleeve 44, through which a headed pin 45 protrudes and engages the end of the lever 41. Upon the under face of the platform and in vertical alinement with the contact-block 42 of the lever 41 are the contact-blocks 46 and 46', which are connected by wires 47', 48 and 47 48', respectively, to the posts 49, from whence the wires pass up through the framework of the car to the contact-blocks 34 and 35. The lever 41 is constructed whereby the contacting end of the lever will be of a sufficient weight to normally hold the pin 45 in an elevated position, as illustrated in Fig. 2 of the drawings. In the casing of my improved indicator are mounted the incandescent bulbs or lamps 50 50, which are con-

nected by wires 51 51 to the car-circuit of electric energy.

Operation: We will assume that it is desired to display the words "Wood street," as illustrated in Fig. 1 of the drawings, and to accomplish this the motorman upon passing the street prior to Wood street presses downwardly with his foot upon the headed pin 45, which raises the contact-block 42 into engagement with the contact-blocks 46 and 46', the metallic piece at each side of the block 42 then spanning the insulation between the two metallic sections of which each of the blocks 46 46' is composed, and a circuit will be completed to operate my improved indicator in either one or the other direction. The reversing mechanism of my improved indicator is adapted to be operated by the conductor of the car, and by rotating the button 32 he can actuate mechanism whereby the indicator will be operated in either direction—that is, whereby the shaft 9 will take up the apron or the shaft 10 will take up the apron. As heretofore stated, the ratchet-wheels upon one end of the shafts differ from the ratchet-wheels upon the opposite end, and I employ the plates 27 and 28 for reversing the travel of the apron. These plates control the pawls 18 and 19, and by referring to Fig. 3 of the drawings it will be observed that the plate 27 is in an elevated position, the body portion of the plate being then interposed between the pawls 19 and the ratchet-wheels and holding the pawls 19 out of engagement with the ratchet-wheels 14, while the plate 28 upon the opposite side is in such a position that the pawls 18 can operate through the slots 29, formed in said plates. (See Fig. 2.) When the button 32 has been rotated to rock the lever 30 and raise the plate 27, the contact-block 35, carried by the shaft 31, is placed in engagement with the contact-block 37 of the casing, and when the motorman depresses the headed pin 45 and completes the circuit through the contact-blocks 46 and 46' the circuit is as follows: The source of electrical energy is the car-circuit, which is connected to the contact-blocks 46 and 46', and the current then passes through one side of the divided contact-block 42, which is now bridging the space between two sections of the contact-block 46' and through the wire 47 to the contact-block 35, contact-block 37, through wires to the solenoid 21, and upon this solenoid being energized the core 24 is raised, carrying with it the post 17, which raises the pawls 18 and rotates the ratchet-wheels 12 sufficiently to unwind the apron from the shaft 9 and wind it upon the shaft 10, displaying the name of the street which the car is approaching. The circuit is completed by a wire 48 to the contact-block 46, from whence it passes, crossing over the portion of the contact-block 42 which is now bridging the

space between the two sections of block 46, by wire 51 through lamp 50 to the other wire of the car-circuit. When the button 32 has been rotated by the conductor, he has placed 5 the contact-block 35 in engagement with the contact-block 37 and has lowered the plate 28 to permit the pawls to operate the ratchet-wheels 12. Simultaneously with this operation the contact-block 34 has been elevated 10 and disengaged from the contact-block 36, thereby breaking the circuit through the solenoid 20 and rendering that solenoid inactive, and the plate 27 has been raised, which 15 disengages the pawls 19 from the ratchet-wheels 14.

Upon all the names of the streets having been displayed by the motorman depressing the headed pin 45 and the end of the route having been reached, the conductor again 20 rotates the button 32, which will break the circuit just described and place the pawls 18 out of operation by the elevation of the plate 28, and upon the car starting upon its route and the motorman depressing the pin 45, the 25 plate 27 having been placed in such a position that the pawls 19 can be operated, the circuit in connection with this operation is as follows: When the headed pin 45 is depressed, the current passes through the wires 30 47' to the contact-block 34, contact-block 36, through the wire 38 to the solenoid, energizing the solenoid, which attracts the core 23 and causes a downward movement upon the pawls 19, which will rotate the ratchet-wheels in the opposite direction from that in 35 which the rolls have been previously rotated, the current returning over the wire 48' to the contact-block 46'. It will thus be seen that with the reversing of the mechanism the circuits are reversed, and with the assistance of 40 the conductor and motorman of the car my improved indicator can be operated to display the different names of the streets of the route over which the car passes. The incandescent lamps 50 are always in circuit 45 with the car-circuit, as is now the common practice, and these lamps are intended to reflect their rays upon the apron containing the names of the streets whereby the occupants of the car can readily observe the same.

What I claim, and desire to secure by Letters Patent, is—

1. In a device of the type set forth, the 55 combination with a car, of a casing mounted in said car, two shafts mounted in said casing, an apron carried by said shafts, ratchet-wheels on the opposite ends of each shaft, a pawl adapted to engage each ratchet-wheel, 60 two solenoids arranged adjacent to said shafts, each solenoid being adapted to oper-

ate two of said pawls, electric circuits including a switch under control of the motorman for energizing said solenoids, and movable plates arranged adjacent to said ratchets at 65 each end of the shafts, each plate being adapted to throw the pawls at the same end of the shafts into and out of action, and means for moving said plates, substantially as described. 70

2. In a device of the character set forth, the combination with a car, of a casing, two shafts arranged in said casing, an apron connected to both said shafts, a ratchet-wheel on each end of said shafts, a pawl engaging 75 each of said ratchet-wheels, electrically-actuated means for moving two of said pawls simultaneously, and movable plates manually operable, and adapted to be alternately interposed between the pawls and ratchet-wheels at one end of the shafts, and the pawls and ratchet-wheels at the other end of the shaft. 80

3. In a device of the character described, the combination with a car, of a casing, shafts 85 mounted in said casing, an apron connected to said shafts and adapted to be wound upon one shaft and unwound from the other shaft, ratchet-wheels mounted upon both ends of both of said shafts, pawls mounted adjacent 90 to said wheels, solenoids carried by said casing and adapted when energized to rotate said ratchet-wheels, mechanism located upon the platform of the car to complete an electric circuit to energize said solenoids, and 95 means carried by the casing for controlling the direction of the movement imparted to said apron by the said electric actuating means.

4. The combination with a car, of an indicator, said indicator consisting of a casing having a sight-opening in one of its sides, shafts rotatably mounted adjacent to said opening, an apron attached to said shafts, a solenoid mounted at each end of said casing, 100 mechanism actuated by one solenoid to rotate both said shafts in one direction, mechanism actuated by the other of said solenoids to rotate both said shafts in an opposite direction, and means adapted to be actuated by 105 the operator of the car to complete an electric circuit passing through said solenoids, and manually-operable means for alternately rendering inactive the solenoid-actuating mechanism at each end of the casing. 110 115

In testimony whereof I affix my signature in the presence of two witnesses.

HARRY A. WATSON.
